US0D1009654S

(12) **United States Design Patent** (10) Patent No.: **US D1,009,654 S**
(45) Date of Patent: ** Jan. 2, 2024

(54) **SURFACE-SUPPORTED, HVAC SENSOR**

(71) Applicant: **Lennox Industries Inc.**, Richardson, TX (US)

(72) Inventors: **Surendran Ramasamy**, Tamil Nadu (IN); **Stephen J. Vendt**, Lewisville, TX (US); **Arun Kunasekaran**, Tamil Nadu (IN); **Melissa del Carmen Amoros Sol**, Richardson, TX (US)

(73) Assignee: **Lennox Industries Inc.**, Richardson, TX (US)

(**) Term: **15 Years**

(21) Appl. No.: **29/834,080**

(22) Filed: **Apr. 8, 2022**

(51) LOC (14) Cl. **10-04**

(52) U.S. Cl.

USPC **D10/50**

(57) **CLAIM**

The ornamental design for a surface-supported, HVAC sensor, as shown and described.

DESCRIPTION

FIG. 1 is a front, left perspective view of a surface-supported, HVAC sensor, showing the new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top view thereof; and

FIG. 7 is a bottom view thereof;

FIG. 8 is a rear right perspective view thereof;

FIG. 9 is a front left perspective view thereof; and,

FIG. 10 is a front bottom, perspective, exploded view thereof.

The broken lines in the Figures show portions of the surface-supported, HVAC sensor, that form no part of the claimed design.

1 Claim, 9 Drawing Sheets
